UNITED STATES PATENT OFFICE.

BENJAMIN BRYAN WAYLAND, OF PORTLAND, OREGON.

WASHING MACHINE.

Application filed October 12, 1925. Serial No. 62,018.

This invention relates to washing machines, one of the objects being to provide a means whereby the fabrics contained in a machine can be subjected to the action of a plurality of jets of cleansing fluid directed thereagainst from opposite directions alternately.

A further object is to provide simple and efficient means for setting up the flow of cleansing fluid in the machine.

A still further object is to provide a machine of this character which does not require the use of any moving parts liable to tear or otherwise injure the fabrics.

15 A still further object is to provide a machine which can be easily cleaned, is formed of relatively few parts, and can be actuated easily.

With the foregoing and other objects in view which will appear as the description proceeds, the invention resides in the combination and arrangement of parts and in the details of construction hereinafter described and claimed, it being understood that changes in the precise embodiment of the invention herein disclosed may be made within the scope of what is claimed without departing from the spirit of the invention.

In the accompanying drawings, the preferred form of the invention has been shown.

In said drawings,

Figure 1 is a central vertical section through a washing machine embodying the present improvements.

35 Figure 2 is a view partly in elevation and partly in section of the pistons forming a part thereof.

Figure 3 is a view partly in section and partly in elevation of a portion of a modified form of cover for the machine.

40 Figure 4 is a section on line 4—4 Figure 1.

Referring to the figures by characters of reference 1 designates a tub preferably cylindrical and mounted on suitable supports

45 2. Mounted on the bottom of the tub is a substantially conical spraying head 3 having a central opening about which is arranged an upstanding tubular core or cylinder 4. The upper end of this cylinder projects into

50 an opening 5 formed in the apex portion of an inverted conical spraying head 6. This head is fitted snugly within the upper portion of the tub and is preferably formed integral with a cover 7 which rests on the tub.

55 Both of the heads 3 and 6 are formed with numerous small apertures indicated at 8 and

the annular space 9 provided between the heads and around the cylinder 4 is designed to receive the fabrics to be cleaned.

A piston 10 is mounted for reciprocation within the cylinder 4 and has a rod 11 connected by a piston 12 to the crank 13 of a drive shaft 14. This shaft can be journaled between the supports 2 and, in the structure illustrated is provided with a pulley 15 whereby it can be driven by the use of a belt or the like. The piston rod 11 is slideable in a suitable bearing 16 provided therefor in the bottom of the tub.

Formed within the piston 10 are ports 17 and each port is normally closed by a valve 18. The valve is held to its seat by a spring 19 which bears against a bracket 20 mounted on the piston. The two valves are oppositely disposed so that when the piston is moving in one direction one of the valves will open under the pressure exerted thereagainst whereas when the piston is moved in the opposite direction the other valve will open.

In using the machine the cover 7 with the head 6 is removed and the fabrics to be cleaned are placed within the space 9. The cleansing fluid is also placed in the tub so as to partly fill it. The cover 7 is then replaced with the head 6 engaging and surrounding the upper end of the cylinder 4. When shaft 14 is actuated piston 10 is caused to reciprocate. Each time the piston moves downwardly the cleansing fluid in the path thereof is forced downwardly into the head 6

90 3 and thence outwardly through the small apertures 8 within said head so as to form jets which will be projected upwardly against the fabrics. During each upward stroke of the piston the cleansing fluid in the path thereof is directed into the head 6 and thence outwardly through the apertures 8 so as to be directed in small jets downwardly onto the fabrics. The impact of the jets of cleansing fluid against the fabrics 95 will result in the rapid cleansing thereof and as the piston is reciprocated in its cylinder 4 a rapid back and forth flow of the fluid is set up.

Instead of providing the cover 7 with a conical head 6 as shown in Figure 1 a cover 21 such as shown in Figure 3 may be used. This cover has a depending cylinder 22 formed with apertures 23 and adapted to project into or fit against the cylinder 4. Consequently during the upstroke of the pistons the water will not be projected down-

wardly in jets but will be projected radially through the openings 23.

What is claimed is:

1. In a washing machine the combination with a tub, and a removable cover thereon, of a conical apertured head upon the bottom of the tub, a cylinder upstanding from the center of the head and communicating therewith, an apertured head carried by the cover and communicating with the upper end of the cylinder, a piston mounted for reciprocation in the cylinder, and means for actuating the cylinder.
- 10 2. In a washing machine the combination with a tub, and a removable cover thereon,

of a conical apertured head upon the bottom of the tub, a cylinder upstanding from the center of the head and communicating therewith, an apertured head carried by the cover and communicating with the upper 20 end of the cylinder, a piston mounted for reciprocation in the cylinder, means for actuating the cylinder, and valves carried by the piston and adapted to open under pressure during successive strokes of the piston 25 respectively.

In testimony that I claim the foregoing as my own, I have hereto affixed my signature.

BEN BRYAN WAYLAND.
